UNITED STATES PATENT OFFICE.

THEODORE R. McDONALD, OF NORTHLVILLE, MICHIGAN, ASSIGNOR TO GEORGE W. HEARTLEY, OF SAME PLACE.

HAT-HANGER.

SPECIFICATION forming part of Letters Patent No. 397,599, dated February 12, 1889.

Application filed June 14, 1888. Serial No. 277,074. (No model.)

To all whom it may concern:

Be it known that I, THEODORE R. McDONALD, a citizen of the United States, and a resident of Northville, in the county of Wayne 5 and State of Michigan, have invented certain new and useful Improvements in a Foldable Hanger for Hats; and I do hereby declare that the following is a full, clear, and exact description of the invention, which will enable 10 others skilled in the art to which it appertains to make and use the same, reference being had to the accompanying drawings, and to the letters of reference marked thereon, which form part of this specification:

15 My invention relates to a foldable hanger for hats, and is designed to be connected with the hat and to fold within the same when not in use, or be unfolded to project sufficiently from within the hat to form a hanger by which 20 the hat can be suspended.

The object of the invention is to provide a cheap and durable hanger that can be removably or permanently secured within a gentleman's or lady's hat, with provision for holding 25 the hanger securely within the hat when being worn, and also to reverse the position of the hanger to cause the same to project from within the crown of the hat a sufficient 30 distance to be engaged with a nail or hook, or with means for expanding jaws to the hanger for engagement with any projecting molding or narrow strip that may extend from the wall 35 sufficiently far to allow the jaws to be engaged.

35 The invention consists in certain parts and combination of parts, which will be fully described, and pointed out in the claims.

In the drawings, Figure 1 is a front elevation of a complete hanger. Fig. 2 is an elevation of a complete hanger folded. Fig. 3 40 illustrates the hanger as applied to a hat in the act of suspending the same, showing also in dotted lines the hanger folded within the crown of the hat. Fig. 4 is an edge view of the body portion of the hanger on lines *xx*, Fig. 2. Fig. 5 is a detail view of one form of fastener for securing the body portion to the hanger, showing the spring secured thereto by means of a rivet. Fig. 6 is a like view of 45 a fastener, showing the spring formed integral.

A designates the body of the hanger, which may be formed of card-board, vulcanized rubber, sheet metal, celluloid, oil-board, or any light flexible material, and is preferably in 55 rectangular form, of a width nearly equal to the ordinary width of the sweat-band of a hat and of a length about three times the width.

To the body portion is secured a metallic fastener, B, of any desired form. For the purposes of illustration it is shown as consisting of a triangular plate, C, with a rectangular portion, D, cut away centrally, as at E, the rectangular portion being bent upon plate C to clasp the body portion between the plate and 60 rectangular portion, and be secured thereto by means of a rivet, F, passed through both portions of the fastener and the body portion A, as well as through a spring, G, secured within the cut-away portion E. 65

In Fig. 6 the spring G is formed integral with the plate. 70

H designates the suspension-wire of the hanger, which is formed of a single piece of wire, the portion connected with the body A 75 or fastener B being bent in an elongated form, as at H, with a central projecting part, H', the free ends of the wire I extending from the elongation in parallel relation to the outer end thereof, where each end is bent in semi-cylindrical form K and K', to form a ring, L, when closed, as shown in full lines, Fig. 2, and in operative position, Fig. 3, or to form a clamp when opened, as shown in dotted lines, Fig. 2. 80

M designates a clasp, embracing the suspension-wires and movable thereon to allow expansion of the jaws when moved downward upon the wires, or to contract the same when moved in an opposite direction. 85

In operation the body portion is placed between the sweat-band and hat-body, and when not in use the suspension-wire is folded back into the crown of the hat, as shown in dotted lines, Fig. 3. When in this position, the projection H' rests against the spring G with sufficient force to hold the suspension-wire in folded position. 90

When it is desired to hang the hat up, the suspension-wire is folded to project outside 100 the crown, as shown in full lines, Fig. 3, and if there is a nail or hook in convenient position

the ring L is slipped thereon. If, however, there is no nail or hook convenient, the clasp is run down sufficiently upon the wires to allow the jaws to open and embrace the edge of 5 a door, a molding, or any projecting frame, and the jaws are tightened by sliding the clasp upward.

If the hanger is used in suspending a lady's hat or bonnet, a pin, B', Fig. 5, is passed 10 through the hat and perforations B'' in the fastener, and the operation is the same as just described.

What I claim, and desire to secure by Letters Patent, is—

15 1. In a hanger for hats, a plate for attachment to the hat, a clip embracing the edge of said plate, provided with hinge-bearings and a spring, and a hanger pivoted in said bearings, provided with a projection on its heel for en-

gagement with the spring, and at its opposite 20 end with a clasping device for suspending the hat, as and for the purpose set forth.

2. In a hanger for hats, a plate, a clip embracing the edge of said plate, provided with hinge-bearings and a spring, and perforations 25 in the plate, in combination with a pin adapted to be inserted in the perforations and through the hat, with a hanger pivoted in the hinge-bearings, provided with a projection upon its heel for engagement with the spring on the 30 clip, as and for the purpose set forth.

In testimony that I claim the foregoing as my own I hereby affix my signature in presence of two witnesses.

THEODORE R. McDONALD.
